SHOULDER PAD

Samuel Bloom, Brooklyn, N. Y.

Original application August 7, 1946, Serial No. 689,000, now Patent No. 2,425,227, dated August 5, 1947. Divided and this application August 2, 1947, Serial No. 765,789.

4 Claims. (Cl. 2—268)

1

This invention relates to improved molded, fitted and shaped shoulder pads for adaptation to garments and particularly women's garments, for imparting desired contour lines to the garments.

This application is a division of my copending application, Serial No. 689,000, filed August 7, 1946, now Patent No. 2,425,227, granted August 5, 1947.

It is the object of the present invention to provide improved sets of molded, fitted and shaped shoulder pads which are fitted to the right and left shoulders of a person in order to conform to the body configurations of the individual and which are so shaped as to obtain desirable shoulder outlines in accordance with different styles and vogues.

It is the purpose of the invention to provide such shoulder pads fitted and graded to individual persons for both right and left shoulders, which maintain their permanence after their fabrication. One person may have several sets of these shoulder pads for different dresses, coats or costumes, in dependence upon the desired style of garment sought to be fashioned or created for the individual wearer.

It is a further object of the invention to provide a shoulder pad which conforms to the body frame of the individual and which is of light and neat construction so that the same can be worn with comfort at all times. The shoulder pad in accordance with the invention may be patterned from standard forms, or may be distinctively patterned from the individual body frame so that any idiosyncrasies characterizing the individual at the clavicle, scapula and acromion may be reflected in the ultimate shape of the finished shoulder pad. Thus, the collarbone or clavicle forming the anterior portion of the shoulder girdle, the scapula or shoulder-blade forming the posterior portion of the shoulder girdle, and the acromion forming the summit of the shoulder, may contribute to the distinctive shaping of the shoulder pad in order to enable one to obtain an individually fitted set conforming to the individual's body contours, which is particularly desirable when such present a substantial departure from those of a standard model.

It is a further object of the invention to pro-

2

vide a shoulder pad embodying a light fabric base and molded felt top corresponding to any desired outline, embodying therebetween a filler of cotton wadding which is maintained in fixed relation between the bottom and top so that once the unit is fitted to the shoulder, the same retains its given contours over long periods of time without sagging or disintegration. The shoulder pad in accordance with the present invention is designed to blend into the lines of the garment in order to render its presence invisible and may, if desired, be detachably connected to the garment so that the same may be used interchangeably in different suits, dresses, coats or the like. Other objects and purposes will appear from the detailed description of the invention following hereinafter, taken in conjunction with the accompanying drawings, wherein:

Fig. 1 is a perspective view of the fitted shoulder pad in accordance with the present invention, adapted for incorporation into any desired garment such as a dress or coat;

Fig. 2 is a longitudinal sectional view of the improved shoulder pad in accordance with the invention, along line 2—2 of Fig. 3;

Fig. 3 is a transverse sectional view along line 3—3 of Fig. 2;

Fig. 4 shows the initial step of molding with clay the desired contour of the shoulder pad which is shown, being done with a model form, but which may as well be executed on a human body;

Fig. 5 shows the molding of the sized felt to bring the same into the shape of the convex top of the shoulder pad;

Fig. 6 is a plan view of two superposed squares of cotton felting which are adapted to embrace therebetween a fibrous filler or cotton wadding to form the internal padding for a pair of the shoulder pads;

Fig. 7 shows a pair of the filler pads of lenticular cross-section at the conclusion of its filling and processing, cut across one diagonal to form the two pads, one for each shoulder pad;

Fig. 8 shows the two filler pads with a wedge removed therefrom in order to permit the concave shaping of the pad to the convexity of the shoulder while imparting a minimum thickness to the pad at the edges thereof as well as a surface of smooth convexity on the upper surface 50 of the pad;

Fig. 9 is a bottom view of the fabric portion of the pad with the filler sewn thereto along lines of stitching spaced from its lateral edges;

Fig. 10 shows the fitting of the shoulder pad following the combination by basting of the padded fabric base with the molded felt top and prior to the trimming of the latter; and

Fig. 11 shows the addition of the wide bands to the lateral edges of the top of the shoulder pad to enable the attainment of a finished and smooth edge for the shoulder pad preparatory to the finishing sewing and cutting operations to obtain the finished shoulder pad shown in Figs. 1 to 3.

The drawings illustrate the complete shoulder pad in accordance with the present invention, as well as several stages in the course of its fabrication. Bearing in mind that the ultimate objective of the invention is to provide an individually tailored and fitted set of shoulder pads which are designed primarily for high grade ladies' garments, it may readily be seen that the manipulative steps which are practiced in the production of this improved set of shoulder pads are painstaking and to some degree costly but all are contributory to the ultimate objective of obtaining a shoulder pad which has never been available heretofore.

The pad in accordance with the instant invention is illustrated in Figs. 1 to 3 in its finished state. The same consists essentially of a soft and light fabric base 11 which may be of any desired textile material such as silk, rayon, cotton or any other known lining materials, which is designed to conform accurately to the shoulder-blade, collarbone and summit of the shoulder of the individual along the lateral edges 13 and 17 which converge to the apex 15 adjacent to the neck line of the individual and which are spanned by the base line 14 between the edges 13 and 17. The desired external outline for the shoulder pad is attained by a sculptured and molded sheet 10 of felt, buckram, flannel or suede, which corresponds in outline to the contours sought to be obtained with the shoulder pads, that is, the pad may incline upwardly, downwardly, or may lie horizontally, or may combine different surface inclinations and may terminate in any desired curvature at the base line 14 to attain different desired silhouette effects. A filling of cotton wadding 18, enclosed within a shell of sheet cotton felting 19, which is sewn to the bottom 11, is shaped in such a manner as, for example, by slitting a wedge at 20, to provide an adequate filling of the space between the bottom 11 and top 10 of the shoulder pad while at the same time enabling the same to be eased to the varying contours of the shoulder. The sewing of the filler shell 19 to the base 11 is shown by means of stitching 21 which is followed by the sewing of the molded and shaped felt 10 to the base by stitches 22 on the sides, and 28 on the end. Wide binding bands 12 are sewed to the lateral edges of the top 10 which preferably may be executed at the same time that the top 10 is sewed to the base 11 by means of stitches 22. The protruding edges of the top 10 are trimmed to follow closely the stitching 22 either before or after the sewing of the latter. A series of parallel stitchings along the binding bands serves to ornament the wide bands and the last lines of stitching 24 also extend through the edges of the base 11 to integrate the complete assembly in order to give a clean and thin edge to the

lateral boundaries of the shoulder pad, which edges, both of the sides 13 and 17, as well as the base edge 14 may be trimmed off with pinking shears in order to impart a more pleasing appearance to the final product (shown in Figs. 1 to 3), as well as to enhance the smooth blending of the edges of the shoulder pad with the garment.

I have found the following procedure most desirable in the fabrication of the improved shoulder pad described above:

Fig. 4 shows the initial stage in the production of an individually tailored set of shoulder pads in accordance with the present invention. In this figure, a conventional clothes model M is employed, but it is understood that a human form may be used as well when a set of individually sculptured shoulder pads is to be attained. If models are used, several of these are necessary to obtain different sizes and grades corresponding to different sizes of human forms. The desired contour of the shoulder pad is sculptured on the model in clay, indicated at C. This, of course, will be varied according to the different vogue and style effects which are sought to be accentuated by the specific shoulder pads. The clay casts of the shoulder pads are permitted to harden, whereupon they are used for the purpose of molding forms therefrom which are employed repeatedly for the fitting and sculpturing of the shoulder pads thereafter. Thus, it is a simple matter to make a counterpart of the clay model C in wood and it is even simpler to make the same in metal by conventional metal casting methods. In addition to the actual shoulder pad counterpart, a replica of the top of the shoulder pad is made by forming two interfitting elements, one of which is preferably formed as a gas heated mold which is used for the molding of the sized felt top of the shoulder pad. It is also useful to form a molded replica of the shoulder outlines in order to provide a base for fitting the bottom of the shoulder pad, particularly so if the model is fragile or if the model is the human body.

The upper part of the shoulder pad 10 is formed from a sheet of moldable felt material of the type used in the manufacture of hats. However, in some instances flannel, buckram, suede, or other moldable cloth materials may be used, and the term "felt" herein should be construed to cover all of these materials. The same is first treated by dipping the sheet in a sizing solution, the concentration of which may be varied in dependence upon the particular felt employed, and may be controlled by testing with the sizing hydrometer. Following the thorough soaking of the felt material in the sizing solution, it is wrung thoroughly and allowed to dry for about twenty-four hours, whereupon the same becomes hard and brittle, but is subject to softening by the application of live steam thereto when the same is placed on a steam grid or like device. In the event that a wooden mold is used, a suitable piece of the felt, of substantially triangular contour, is applied to the wooden mold and is pulled into shape and thereafter the same may be tied with blocking cords until the felt is made to correspond to the shape of the wooden model. A steam iron may be employed to make the felt conform closely to the block and to impart a permanent set thereto. Thereafter the pressed felt is allowed to dry on the mold until the same is cool, so that the resultant product constitutes the top of the mold 10 as generally shown in Fig. 10 of larger area than

the finished product because the same requires trimming.

As an alternative to the use of a wooden mold and the shaping of the sized felt thereto, metal dies may be employed, preferably of aluminum, as shown in Fig. 5, and one or both of the co-operating members 31 and 32 may be gas heated in order to shape the sheet 30 by heat and pressure, and with the aid of steam to bring it in conformity with the cooperating parts of the mold to impart a permanent set thereto.

Having shaped the upper part of the shoulder pad 10, the fitting of the bottom of the pad is undertaken with the use of suitable patterns which are of substantially triangular outline. Suitable segments of fabric are cut out according to these patterns, depending upon the size and style of the ultimate desired pad. These paper patterns include perforated lines to indicate the lines of stitching whereat the filling material is to be attached to the fabric base in a manner well known to the tailoring and dressmaking arts. The triangular fabric bottom of the shoulder pad is shown generally in Fig. 9 having an apex 35 with the lateral sides 36 and the base line 37, with the stitching lines 21 parallel to the lateral edges which secure the filling shell thereto and which lines are marked in the cutting of the patterns.

Fig. 6 shows in plan two square sheets of cotton felting 19 between which are adapted to be sandwiched a mass of cotton wadding 18 which is of maximum thickness at the center of this square and which tapers smoothly to the perimeter thereof in order to impart a lenticular or double convex cross-section to the filler pad. Thereafter a series of loose stitches 29 are basted through the covering sheets 19 and enclosed mass of wadding 18, as shown generally in Fig. 7, to maintain the filler mass in the form of an integrated filler shell with maximum thickness at its center and of a thickness corresponding to the thickness of the loose cotton sheets of felting 19 at the edges. The square is subsequently cut along one of its diagonals 37 to form two filler sections, one for each of the pair of shoulder pads. Thereafter a wedge of the wadding, including one face of the sheeting 19 is cut out medially thereof at the base 37 and extending towards the apex 35, and this filler unit is sewed to the fabric bottom 11 of the shoulder pads along the stitches 21 with the wedge adjacent to the fabric so that the same may be shaped concavely to conform to the convexity of the shoulder while the opposite face of the filler is of smooth configuration to fill out fully the convexity of the upper part of the shoulder pad.

The fabric bottom 11 having the filler unit sewed thereto, is thereafter applied to the shoulder mold and is manipulated to conform thereto by drawing and shaping the wadding, upon which is superposed the prepared molded felt as described above and as shown in Fig. 10. When the pads have assumed the desired shape, the fabric bottom and the molded top are basted together, as shown in Fig. 10.

The finishing bands 12, of approximately 2" width, which have previously been stitched on a multiple needle machine, are then applied to each lateral edge of the top of the shoulder pad by means of basting stitches 42 in order to obtain a precision fit thereof onto the edges of the shoulder pad. With the bands 12 sewed in place, it is possible to trim off the excess edges of the molded felt material 10' protruding beyond and below the inner boundaries of the bands, leaving an edging of

the felt for stitching to the bands. The partially assembled pad is then taken to the sewing machine and the bands are stitched as basted along the line of threads 22. Also the outer base edge 14, holding the soft shirred material, as well as the molded outer surface, are then stitched together by the row of stitching 28 after any excess felt is removed from the open end of the filler pad, which is evidenced in the preliminary fitting of the pad when the parts are partially basted together.

The above operations are followed by a trimming of the bands 12 to bring them into conformity with the patterned cut of the fabric bottom of the shoulder pad whereafter a line of stitching 24 serves to integrate the outer margins of the trimming bands 12 with the lateral edges of the bottom 11. These operations are followed by a pinking of the lateral edges at 13 and 17, as well as the base at 14 to impart a finished appearance to the shoulder pads. A stiff binding thread may be applied to the edge 14 if desired in lieu of or in addition to the pinked edge.

A final fitting of the pad to the model shoulder may be employed to impart the finished set to the shoulder pad, which may be aided by the use of a steaming iron.

If desired, snap fasteners or the like may be applied to the apex and the lateral edges of the shoulder pad designed for cooperation with suitable fasteners in the garment to render the shoulder pads readily attachable and detachable relative to the garment, as is well known in the art.

While the preferred embodiment of the invention contemplates a bottom of light fabric, it is perfectly feasible to use a bottom of heavy material together with the moldable top, particularly in the case of heavy or winter garments. Thus the bottom may also be formed of felt, flannel, buckram or suede cloth and may be the same or different from the molded material forming the top of the shoulder pad.

While I have described my invention as embodied in a specific form and as operating in a specific manner for purpose of illustration, it should be understood that I do not limit my invention thereto, since various modifications will suggest themselves to those skilled in the art without departing from the spirit of my invention, the scope of which is set forth in the annexed claims.

I claim:

1. A molded shoulder pad composed of a substantially triangular flexible fabric bottom fitted to the wearer's shoulder with the apex of the triangle at the neck line, an overlying molded felt top shaped to the desired contour and an intermediate filling of wadding sewn to said fabric base with shirring at the side opposite said apex, said filling being of increasing thickness from the edges adjoining the apex of the pad to the base of said pad with a wedge cut from the lower face thereof extending from said base towards the apex to permit the bottom of the pad to assume a concavity conforming to the convexity of the shoulder while the top may assume a convexity conforming to that of the molded felt top, and lines of stitching joining the felt top to the fabric base along the three sides thereof.
2. A molded shoulder pad as set forth in claim 1, provided with trimming bands sewn to the two lateral sides of the molded felt top adjoining

the apex and overlying the lateral edges of the fabric base.

3. A molded shoulder pad as set forth in claim 1, provided with trimming bands sewn to the two lateral sides of the molded felt top adjoining the apex and overlying the lateral edges of the fabric base, lines of stitching joining the outermost edges of said trimming bands and fabric base and pinked edges therebeyond.

4. A molded shoulder pad as set forth in claim 1, wherein at least the lateral sides of the shoulder pad beyond the stitching are pinked.

SAMUEL BLOOM.
